Le Grand Kniffen
By Chas. A. Gillman, Atty.

UNITED STATES PATENT OFFICE.

LE GRAND KNIFFEN, OF CHICAGO, ILLINOIS.

TRACTION-BAND FOR WHEELS.

SPECIFICATION forming part of Letters Patent No. 757,471, dated April 19, 1904.

Application filed September 28, 1903. Serial No. 174,870. (No model.)

To all whom it may concern:

Be it known that I, LE GRAND KNIFFEN, a citizen of the United States, residing at Chicago, in the county of Cook and State of Illinois, have invented certain new and useful Improvements in Traction-Bands for Wheels, of which the following is a specification.

This invention relates to improvements in a traction band or attachment to be applied to vehicle-wheels, and while it is more especially applicable for use on wheels of that class of vehicles or machines which carry gearing operated by the rotation of the traction-wheels to perform various functions—such as in the case of manure-spreaders, mowing-machines, fertilizer-distributors, and the like—where it is desirable to have continuous rotation of the traction-wheels, so as to afford positive and continuous action of the gearing driven thereby, yet it may be applied to wheels of other kinds of vehicles; and it consists in certain peculiarities of the construction, novel arrangement, and operation of the various parts thereof, as will be hereinafter more fully set forth and specifically claimed.

The principal object of the invention is to provide a traction band or attachment which shall be so constructed as to increase the rolling friction between the wheels and the road or ground on which they travel, thus preventing them slipping.

Another object of the invention is to construct the band or attachment in such a manner that it will automatically discharge in the rotation of the wheel to which it is applied mud or earth adhering or clinging thereto.

Another object is to form the band so that it may be adjusted to wheels of different sizes and may be easily repaired in the event of any of its parts being broken.

Other objects and advantages of the invention will be disclosed in the subjoined description and explanation.

In order to enable others skilled in the art to which my invention pertains to make and use the same, I will now proceed to describe it, referring to the accompanying drawings, in which—

Figure 1 is a view in side elevation of a wheel with a traction-band embodying one

form of my invention in place thereon. Fig. 2 is an end or edge view of the wheel and a face view of the band, showing the latter in position on the former. Fig. 3 is an enlarged plan or face view of a portion of the band. Fig. 4 is an edge view thereof. Fig. 5 is a view of one of the ends of one of the links comprising the band. Fig. 6 is a view of the other end of said link, showing it interlocked with the adjacent link thereto. Fig. 7 is a reduced plan or face view of a portion of the band, showing a modification in its construction; and Fig. 8 is a similar view of one of the interlocking links comprising said modified form.

Like numerals of reference refer to corresponding parts throughout the different views of the drawings.

The band comprises a series of open and interlocking links which are counterparts of one another and are substantially diamond-shaped in outline. Each of these links consists of two slightly-curved members 15, having their ends approximated and united by raised transverse portions 16 and 17, the portion 16 being provided on its inner surface, or that surface adjacent to the tire or felly 18 of the wheel 19, with a recess 20 to receive the members 15 of the adjoining link near their ends. The transverse portion 17 on each of the links extends laterally beyond each side of the members 15 and is slightly raised outwardly, so as to rest on the outer surface of the flattened or reduced portions 21 of the members 15, which reduced portions diverge and extend to about the middle of the members 15, or the widest portion of the link. From the inner ends of the reduced parts 21 the members 15 are enlarged to form outwardly-raised parts 22, which extend to the transverse portion 17, as is clearly shown in Figs. 3 and 4 of the drawings. Each of the members 15 is provided on its surface adjacent to the tire or felly 18 with a lug 23, which engages the edge of the tire or felly, as is apparent.

By reference to the drawings and from the foregoing it will be seen and clearly understood that the links may be joined together, so as to form a continuous piece or band of

sufficient length to circumscribe or rest on the outer surface of the tire of the wheel, when said band may be tightened circumferentially thereon by means of bolts 24 and nuts 25, which 5 bolts pass through suitable openings in the transverse portions 26 of the adjusting-links 27 and 28, which may be of any suitable construction, but preferably of the form shown in Figs. 3 and 4 of the drawings, in which the link 27 10 is provided with a transverse portion 29 to engage the portion 17 of the adjoining main link, and the link 28 is provided with a transverse portion 30 to engage the portion 16 of the link adjacent thereto. Each of the adjusting-links 27 and 28 is provided on its inner 15 surface at each end of the transverse portion 26 with an inwardly-projecting lug 31 to engage the edge of the tire 18 or felly.

In Figs. 7 and 8 of the drawings I have shown 20 a modification in the construction of the links comprising the band or attachment, each of which consists of a diamond-shaped link provided at one of its ends with a countersunk T-shaped extension 33, which engages the adjacent end of the adjoining link. As shown in 25 Fig. 8, the countersunk recess 32 is formed on the inner surface of the link, or that surface adjacent to the tire when the band is in position on the wheel. The inner surface of the link is also 30 provided at its widest portion and on each edge thereof with a lug 34 to engage the edge of the tire or felly. The outer surface of one end of each of the links in this modified construction is provided with a groove 35 to receive a portion 35 of the extension 33 on the adjacent link. Two of the parallel portions of the members 36 comprising the links of the modified form shown in Figs. 7 and 8 are outwardly raised, as at 37, while the other two parallel portions are 40 depressed or flattened, as at 38, which construction will cause the mud or earth to slide obliquely from the tire of the wheel in its revolution, whereas in the construction illustrated in Figs. 1 to 6, inclusive, the mud or 45 earth clinging to the wheel will be discharged

through the openings provided by means of the flattened or reduced portions 21 of the links.

From the foregoing it is apparent that the band or attachment can be readily applied to 50 the tire of the wheel by simply tightening the nuts 25 on the bolts 24, which, together with adjusting-links 27 and 28, may be employed on either of the constructions.

In the event of one of the links being broken 55 it is evident that it may be readily replaced and the band again attached to the wheel.

Having thus fully described my invention, what I claim as new, and desire to secure by Letters Patent, is—

1. A traction-band, comprising a series of interlocking links having lugs on one of their surfaces to engage the tire or felly, and means to tighten the band circumferentially on the wheel, substantially as described.

2. A traction-band comprising a series of interlocking links having lugs on their inner surfaces to engage the tire or felly and raised portions on their outer surfaces, and means to tighten the band circumferentially on the 70 wheel, substantially as described.

3. A traction-band comprising a series of links united together, each link consisting of two members having their ends approximated and provided at one of their ends with a recess and at their other ends with a transverse portion, substantially as described.

4. A traction-band comprising a series of links united together, each link consisting of two members having their ends approximated 80 and provided at one of their ends with a recess and at their other ends with a transverse portion, said members also having on one of their surfaces lugs to engage the tire or felly and on the other surface raised portions, sub- 85 stantially as described.

LE GRAND KNIFFEN.
